(57) **CLAIM**

The ornamental design for a portion of an infusion solution bag, as shown and described.

DESCRIPTION

FIG. 1 is a perspective view of a portion of an infusion solution bag according to the invention.

FIG. 2 is a front view of the design according to the invention.

FIG. 3 is a rear view of the design according to the invention.

FIG. 4 is a top plan view of the design according to the invention.

FIG. 5 is a bottom plan view of the design according to the invention.

FIG. 6 is a right side view of the design according to the invention.

FIG. 7 is an enlarged detail view of the design according to the invention.

FIG. 8 is a section view of 8—8 from FIG. 7 of the design according to the invention; and,

FIG. 9 is a section view of 9—9 from FIG. 7 of the design according to the invention.

The dash-dot-dash broken lines in the drawings represent the bounds of the claimed design while all other broken lines are directed to environment and are for illustrative purposes only; the broken lines form no part of the claimed invention.

1 Claim, 5 Drawing Sheets
